UNITED STATES PATENT OFFICE.

HENRY B. ABEL, OF VALLEY STREAM, NEW YORK.

SHOPPER'S CATALOGUE.

1,254,560.

Specification of Letters Patent. Patented Jan. 22, 1918.

Application filed September 13, 1916. Serial No. 119,832.

To all whom it may concern:

Be it known that I, HENRY B. ABEL, a citizen of the United States, and a resident of Valley Stream, in the county of Nassau 5 and State of New York, have invented a new and Improved Shopper's Catalogue, of which the following is a full, clear, and exact description.

This invention relates to shoppers' catalogues or the like and has particular reference to improvements in devices analogous to the device shown and described in Letters Patent of the United States issued to me on August 22, 1916, No. 1,195,761, which 10 15 20 pertains to a shopper's catalogue, each page of which carries one or more main designs and a corresponding number of miniature designs identical with respective main designs, the miniature designs being separable along predetermined lines from the main portion of the page.

Among the objects of the present improvement is to provide a catalogue illustrating merchandise, said catalogue comprising a 25 series of leaves or their equivalent, each leaf of which carries a main design or a series of main designs, while there is associated with each of said leaves one or more coupons each carrying one or more miniature designs 30 corresponding to the main designs of the same leaf, provision being made for the removal of any of the coupons from any of the main leaves, either singly or all together, without impairing the printed matter of the 35 main portion of the book, means being provided to preserve all of the miniature portions of the book as a unitary booklet when removed bodily or as a whole from the main portion of the book.

40 By the term "catalogue" as used herein I mean to cover broadly any analogous publication, regardless of its size, form or construction, designed to describe, list or illustrate wares or merchandise, and whether it 45 is provided with an outside cover or not.

In the drawings, Figure 1 is an elevation of one form of the invention;

Fig. 2 is a similar view of a modification of the same invention; and

50 Fig. 3 is a fragmentary view of a further adaptation.

Referring now especially to Fig. 1, I show a catalogue comprising a plurality of leaves, each leaf being understood to carry on either 55 side one or more main designs, shown in this case as four in number and listed as

has been done heretofore by distinguishing stock numbers. For the purpose of this description, I am identifying these main designs with the letters *a*, *b*, *c*, and *d*. The 60 several leaves constituting the catalogue are bound together by suitable means, such as staples 10.

At any convenient part of the catalogue along the back portion thereof, are provided 65 for each leaf 11, one or more detachable coupons 11^a or 11^b. These coupons are detachable from the main portions of the leaves 11 along predetermined lines, shown in Fig. 1 as weakened lines or perforations 12. The 70 coupon 11^a carries on its face a miniature reproduction of the main design or designs, appearing upon the leaf of which the detachable coupon 11^a is a physical part. The coupon 11^b may carry a miniature representation of a portion of the main design or 75 group of designs pertaining to the same leaf as does the coupon 11^a, or it may be left blank for the purpose of carrying data, such as stock number, size, color, price, material 80 or the like. When thus used the coupon 11^b will ordinarily be removed from the main leaf along with the coupon 11^a and carried by the shopper in her purse or the like for use at the store, thereby obviating the necessity 85 for carrying the entire catalogue with her or occasioning the mutilation or destruction of the catalogue by tearing out a whole leaf as is so commonly done.

13 and 14 represent portions of the leaves 90 formed by the perforations 12 and 16. 15 indicates means to secure all of the portions 14 permanently together. By providing each of these sheets or leaves with weakened lines 16 between the portions 13 and the 95 main portions of the leaves, all of the coupons may be removed from the catalogue as a whole and be carried intact as a permanent booklet without materially damaging or destroying the main catalogue. 100 Among the purposes of the portion 13 is to provide a permanent attachment for either of the coupons 11^a or 11^b, especially the latter when the other coupon is removed from the booklet. The binding means, namely, 105 the strips or portions 14 and staples 15, for the removable coupons supplement the main binding staples 10 for holding the leaves of the complete catalogue together, furthermore, they serve as a means to bind the coupons permanently together when removed 110 bodily as a separate booklet from the main

part of the catalogue. Said coupons are all superposed with respect to one another, as are also said binding strips or portions, and the weakened lines bounding them all register, whereby the detachment of the booklet as a whole from the original is facilitated and the appearance of both the booklet and the remaining main catalogue, after separation, is improved.

10 The modified form of catalogue, shown in Fig. 2, while being similar to that of Fig. 1 in providing a removable portion of the structure constituting a complete miniature booklet, differs from Fig. 1 in that a portion 15 or portions of the weakened lines connecting the removable coupons from the main leaves are slitted, as indicated at 17 and 18, instead of being only perforated, as indicated at 12', and the removable portion 20 of each leaf is shown remote from all of the free edges of the leaf, whereby the removal of the coupon or coupons is not so likely to impair the strength or permanency of the main leaf or leaves or mar the beauty 25 thereof as would result if the coupons were torn from the free edges of the leaves. In this form of the invention I provide the portions 14' through which the permanent fasteners 15 operate for the purpose of 30 binding all of the leaves of the miniature booklet permanently together when the booklet is removed as a whole from the catalogue, as in the other form of the invention. The line 12' connecting each coupon 35 to its portion 14' is preferably a perforated line, and the lines 16' which extend from the slits 17 to the back of the book are perforated lines extending along portions of the upper and lower edges of the coupons. 40 These portions 16' of the weakened lines serve to insure that while the leaves 19 of the catalogue are being turned, the respective coupon leaflets 19' will turn individually with their respective leaves, and yet 45 with the weakened lines 17 and 18 in the form of open slits, leaving a portion of each coupon free in the nature of a tongue, the removal of any coupon 19' independently of all of the others is greatly facilitated. This 50 partial slitting of the weakened lines is of special importance with respect to any leaf having its coupon or removable portion located remote from all free edges of such leaf. By slitting portions of the lines 55 bounding the removable coupon, that part of the coupon bounded by the slits forms a tongue. Without the slitting as just indicated it would be inexpedient, if not impossible, for the shopper to grasp and re- 60 move the coupon without using a sharp pointed instrument to initiate such removal, a practice or condition repugnant to my whole plan or scheme of convenience and facility for shopping. Moreover, with the 65 slitted corner or the tongue portion of the

coupon disposed remote from the binding means or hinge line of the book, it is very easy for the shopper to grasp the coupon with her fingers when an adjacent portion of the main leaf is deflected or bent away 70 from the plane of the coupon.

The variation in Fig. 3 has features corresponding to both those of Figs. 1 and 2. For example, the leaf of the miniature booklet 20 is indicated as carrying on its 75 face a plurality of miniatures *e'* and *f'* corresponding respectively to the main designs *e* and group *f*, shown in Fig. 2, and partially shown in the main portion of Fig. 3. This illustration in Fig. 3 carries out the idea 80 that for the display of certain merchandise one set of main designs may require different degrees of reduction in making the miniature designs, and hence it is useful, if not essential, in such cases to provide independently removable coupons for the accommodation of such different reproductions. Fig. 3, like Fig. 2, provides a miniature booklet removable from an intermediate portion of the catalogue, while in Fig. 90 1, the booklet is removable from a corner portion, but the main features are the same in all the different forms illustrated.

The portion of the catalogue that is removable from the main portion thereof constitutes in effect a miniature booklet, all of the leaves of which may remain bound and held together permanently when detached from the main portion of the catalogue. This booklet is not only miniature in its own 95 construction with respect to the main portion of the catalogue, but may properly be called miniature because it carries the miniature designs relating to the main designs 100 on the respective leaves from which the 105 leaves of the miniature booklet are taken. Furthermore, the miniature booklet may constitute a key to the main catalogue, said key being easily carried in one's purse or shopping bag when to carry the entire catalogue would be inconvenient or impracticable. 110

I claim:

1. A catalogue comprising a plurality of leaves and means to hold said leaves together in a permanent assemblage, each leaf having a small portion removable from the main portion along predetermined weakened lines, a portion of said lines being slitted remote from said holding means, said removable portions of the leaves being superposed with respect to one another with their bounding lines all registering and hence being removable all together simultaneously, and said leaf holding means including binding means serving to hold the detachable parts together prior to and after their removal as an independent complete booklet from the main part of the catalogue. 115

2. A catalogue comprising a plurality of 120

leaves bearing main designs and means to hold said leaves together in permanent assemblage, the several leaves comprising small portions adjacent to said holding means and bearing small designs pertaining to the main designs on the same leaves, said small portions being bounded by predetermined registering weakened lines, parts of said leaves constituting binding strips connected to said several small portions respectively, and said leaf holding means including means fastening these several small portions and binding strips together in the original catalogue in a manner providing for the removal of all of the small portions together simultaneously, including the binding strips, as a distinct booklet constituting a key to the main designs of the catalogue.

3. The herein described shopper's catalogue comprising a plurality of leaves and means to hold said leaves together in a permanent assemblage, any leaf of said plurality having a small portion remote from all free edges of the main portion of said leaf and removable from the main portion of the leaf along predetermined weakened lines, a portion of said lines being slitted to present free edges remote from said holding means, thereby forming the portion of the leaf bounded by the slitting into a tongue to facilitate the grasping and removal of said removable portion.

4. A shopper's catalogue having at its bound edge intermediate of its upper and lower ends a portion outlined by weakened intersecting lines extending through all the leaves of the catalogue including a bound

part of the catalogue, and having within the outlined portion a weakened line adjacent to and parallel with the bound edge and extending through all the leaves, said portion containing reference data relating to the subject matter contained in the body of the catalogue, whereby the said portion may be removed in its entirety to form a pocket reference book, or the parts thereof may be separately removed.

5. A shopper's catalogue having at its bound edge intermediate of its upper and lower ends a portion outlined by weakened and slitted intersecting lines extending through all the leaves of the catalogue, said portion including a bound part of the leaves, the slitted portions of said lines being remote from the bound edge and on three sides of the said portions, said catalogue having within the outlined portion a weakened line adjacent to and parallel with the bound edge and extending through all the leaves thereof, the said outlined portion containing reference data relating to the subject matter contained in the catalogue.

6. A shopper's catalogue having at its bound edge a portion outlined by weakened intersecting lines, extending through all leaves of the catalogue and including a bound part of the catalogue, said portion being smaller than the catalogue and containing on its several leaves reference data relating to the subject matter contained on the several leaves respectively constituting the body of the catalogue, and adapted to be removed to form a pocket reference book.

HENRY B. ABEL.
